(57) **CLAIM**

I claim the ornamental design for a tool, as shown and described.

DESCRIPTION

FIG. 1 is a first perspective view of the tool;

FIG. 2 is a front view of the tool;

FIG. 3 shows a back view of the tool;

FIG. 4 shows a first side view of the tool;

FIG. 5 shows a second side view of the tool;

FIG. 6 shows a top side view of the tool; and,

FIG. 7 shows a bottom side view of the tool.

The broken lines in the drawings illustrate portions of the tool and form no part of the claimed design.

1 Claim, 4 Drawing Sheets
